LAMP HOLDER FOR DOUBLE ENDED
TUBULAR LAMPSBenjamin C. Webster, Southport, Conn., assignor
to The Bryant Electric Company, Bridgeport,
Conn., a corporation of Connecticut

Application April 19, 1948, Serial No. 22,011

13 Claims. (Cl. 173—328)

1

My invention relates, generally, to lamp holders for tubular discharge lamps and, more particularly, to a lamp holder for use with double-ended fluorescent lamps of the semi-circular type.

The object of my invention, generally stated, is to provide a lamp holder which shall be of simple and economical construction, and which may be readily used in pairs for mounting a single semi-circular lamp, or a pair of such lamps in end-to-end relation to provide a complete circle, or any other desired combination of lamps.

A more specific object of my invention is to provide a lamp holder which is of dual or double-sided construction whereby lamps may be plugged in on opposite sides so that one holder supports the adjacent ends of two semi-circular lamps.

Another object of my invention is to provide a holder of this general type wherein definitely spaced contact members for receiving the spaced contact pins of the lamp are mounted in a hollow supporting housing for limited movement in a direction so as to accommodate itself to dimensional variations in lamp manufacture.

Another object of my invention is to provide a holder of this general type wherein a pair of contact members are mounted in spaced relation on a carrier or moulding which is movably mounted within a hollow supporting housing so as to accommodate itself to dimensional variations of the lamp manufacture.

A further object of my invention is to provide a lamp holder of the double-sided construction having two sets of contact members or contact assemblies mounted for limited independent movement within the housing in such directions as to accommodate themselves to dimensional variation in lamp manufacture.

Another object of my invention is to provide a lamp holder of the double-sided construction wherein the contact assemblies mounted adjacent the opposite sides or faces of the holder are so constructed as to provide telescoping or overlapping positioning of the contact pins of the lamps so as to reduce the thickness of the holder to a minimum.

A further object of my invention is to provide, in a lamp holder of this type, for relieving strain on the ends of the wire leads and contact members within the housing without interfering with the freedom of movement of the contact carrier within the housing.

Another object of my invention is to provide, in a lamp holder of this type, for retaining all of the movable parts of the holder in their work-

2

ing relation by means of a two-piece housing comprised of complementary halves of sections.

These and other objects of my invention will become more apparent from the following detailed description when read in conjunction with the drawing, in which:

Fig. 1 is an outside face view, in elevation, of a lamp holder embodying the principal features of my invention;

Fig. 2 is a side view, in elevation, of the lamp holder of Fig. 1;

Fig. 3 is an inside face view, in elevation, of one-half of the complete holder as shown in Fig. 1;

Fig. 4 is a view in section of the portion of the holder shown in Fig. 3 taken along lines IV—IV with the plate of Fig. 6 in position;

Fig. 5 is a bottom view of the holder of Fig. 1;

Fig. 6 is a face view, in elevation, of one of the insulating plates;

Fig. 7 is an end-elevational view thereof;

Fig. 8 is a front view, in elevation, of one of the contact carriers or mouldings;

Fig. 9 is a cross-sectional view taken along lines IX—IX of Fig. 8;

Fig. 10 is a back view, in elevation, of one of the contact carriers;

Fig. 11 is a cross-sectional view taken along lines XI—XI of Fig. 10;

Fig. 12 is a side-elevational view of a contact element;

Fig. 13 is an end view thereof;

Fig. 14 is an exploded view of the various parts of a complete lamp holder showing their relative positions when assembled; and

Fig. 15 is a view showing one way in which two of the lamp holders of my invention may be used to support a pair of semi-circular lamps.

In practicing my invention in the preferred form, the holder is comprised of a hollow two-piece supporting housing of insulating material in which are mounted a pair of contact carriers or mouldings also made of insulating material, a pair of plate members interposed therebetween, and a pair of metallic contact members carried by each carrier. The housing is preferably made up of two complementary halves or sections held together by eyelets or hollow rivets and having internal recesses to provide the necessary cavities for holding the contact carriers and other parts. The bottom or base portion is provided with two elongated and spaced apart openings to receive the lead wires or conductors with a clamping action, and with mounting screws which engage nuts held within suitable cavities. The opposed

outer faces or surfaces of the housing are generally flat and parallel and are provided with pairs of elongated openings spaced apart to receive hollow projections or bosses on the contact carriers in which the spaced lamp prongs are received, with the openings in offset relation. All of the corresponding parts or elements of the holder are of identical construction.

Referring now to the drawing and to Fig. 14 in particular, there is shown one embodiment of my invention in the form of a double-sided lamp holder comprising, generally, a pair of housing sections 20 and 21, a pair of contact carriers or mouldings 22 and 23, two pairs of contact members 24-25 and 26-27 and a pair of plates 28 and 29. In this view, these parts are shown in a separated or exploded form so as to bring out their relationship when assembled into a unitary structure.

Referring now to Figs. 1 and 2, it will be observed that the housing sections 20 and 21 may be held together by means of suitable riveted eyelets or screws 31 extending through openings as shown. Each housing section is provided with a pair of elongated openings spaced apart at least a sufficient distance to receive the lamp prongs. As shown in Fig. 1, the housing section 20 is provided with openings 32 and 33. The other housing section 21 is provided with similar openings. The centers of these openings are preferably disposed on opposite sides of the longitudinal or vertical axis of the housing and lie on a line which extends at an angle of about 45° to the longitudinal axis. In Fig. 1 the upper opening 32 is at the right and the lower opening 33 at the left-hand side of the face shown. On the opposite face of the housing, the openings corresponding to these openings 32 and 33 are reversed and their centers lie on a line which extends at an angle of about 45° to the longitudinal axis but at an angle of about 90° with the line extending through the centers of the openings 32 and 33.

Referring now to Fig. 3, which shows an internal view of one-half of the holder, i. e., the back half as viewed in Fig. 1, it will be observed that the housing section 21 is recessed to provide a deep rectangular recess or cavity 34 in its upper end. A pair of shallower U-shaped passages or channels 35 and 36 extend from the bottom of the housing section upwardly toward the recess 34 and merge with it through a wider recess 37.

As shown, the ends of the lamp cords or conductors 41 and 42 extend through these passages 35 and 36 to their respective contact members 26 and 27 in the carrier. It is to be understood that the other housing section 20 is constructed in the same manner to accommodate the other pair of conductors 43 and 44 so that when the two sections are placed together as shown in Figs. 2 and 5, two spaced apart bottom openings are formed to receive both pairs of conductors.

In order to effectively clamp the ends of the conductors between the housing sections and thereby provide for relieving the inner ends of these conductors and their associated contact members from undue strain such as might interfere with the free movement of the carriers 22 and 23 or break the electrical connections within the housing, each of the passages 35 and 36 as well as the corresponding passages in the other housing section may be so formed as to effectively grip the conductors when the housing sections are fastened together.

As shown in Fig. 4, the passage 36 may be provided with a relatively sharp clamping lug or

projection 45 which bites into or indents the insulation of the conductor 42 to such extent as to effectively hold it at the desired position. The other passage 35 of this housing section may have a similar projection 46 as shown in Fig. 3. The corresponding passages in the other housing section 20 may have similar projections so that each conductor is properly gripped between the sections so as to provide adequate strain relief.

Two smaller spaced apart recesses are provided at the bottom of each housing section to receive the mounting screws and hold their nuts in place. As shown in Fig. 3, the housing section 21 has recesses 47 and 48 of sufficient depth to receive one-half of the bolts 51 and 52 and nuts 53 and 54. The other housing section 20 has similar and matching recesses so that when the sections are placed together as in Fig. 2, the nuts 53 and 54 are held against turning and serve as anchors for the bolts 51 and 52.

Fig. 3 shows the manner in which the contact carriers and their associated contact members are mounted in the housing sections. The contact carrier 23 is positioned within the rectangular recess 34 and is of such size that it may move transversely as well as longitudinally of the housing section to a limited degree. This view also shows one pair of the contact members 26 and 27 positioned in the carrier 23 and attached to their leads 41 and 42.

Referring now to Figs. 8 through 11, which show the details of the identical contact carriers 22 and 23, it will be observed from Fig. 8 that the carrier 23, for example, is provided on its front surface with hollow projections or bosses 57 and 58 having openings 59 and 61 to receive the contact pins of the lamp. These hollow projections extend through elongated openings in the face of the housing section 21 similar to the openings 32 and 33 shown in Fig. 1.

Fig. 10 shows the details of the back face of the carrier 23 which is provided with a long L-shaped shallow recess 62 and another shorter L-shaped shallow recess 63 connecting the lower edge of the carrier with openings 59 and 61, respectively. The recess 62 has an extending portion 64 below the opening 59 which corresponds generally in shape to another shallow recess 65 above the other opening 61.

As shown in Fig. 3, the L-shaped recesses 62 and 63 are for the purpose of receiving and holding the contact members 26 and 27 and the ends of their lead wires. The purpose of the recesses 64 and 65 is to receive the ends of the lamp pins extending through the other pair of contact members 24 and 25 mounted on the other carrier 22.

It will be understood that this assembly of the contact carrier 22 and its contact members 24 and 25 are reversed in the housing with respect to the assembly just described including contact carrier 23 so that when it is placed in facing relation thereto with its contact members mounted in the L-shaped recesses, the ends of the other pair of lamp pins extending through contact members 26 and 27 will be received by its recesses corresponding to recesses 64 and 65 in the carrier 23.

It is apparent that this permits of a telescoping arrangement or positioning of the contact pins of the two lamps within the housing and reduces the thickness of the lamp holder, thereby holding the spacing between the adjacent ends of the lamps to a minimum.

In view of the foregoing, it will be apparent

that two independently movable or floating contact assemblies are provided which effectively compensate for all permissible manufacturing variations in the lamps. The lamp pins engage the contact members on the carriers directly through the large elongated openings in the opposite faces of the housing and the smaller openings through the bosses of the carriers.

Plates 28 and 29 are identical and the details of plate 29, for example, are shown in Figs. 6 and 7. As shown in Fig. 6, the plate 29, which is preferably formed of thin insulating material, is provided with a pair of elongated openings 66 and 67 and a pair of small openings 68 and 69. As will be observed, the elongated openings 66 and 67 have the same relative locations as the recesses 64 and 65 in the carrier, and that the small openings 68 and 69 have the same relative locations as the openings 59 and 61 in the contact carrier 23. In other words, the diagonally opposite openings in the plates have their centers on intersecting lines disposed at an angle of about 90° to each other and at an angle of about 45° from the vertical.

The insulating plate 29, for example, fits upon the contact assembly as shown in Fig. 4. The small openings 68 and 69 receive projections on contact members 26 and 27 which extend outwardly from the face of the carrier, and the elongated openings 66 and 67 line up with the elongated recesses 64 and 65 in the carrier 23.

Figs. 12 and 13 show the details of the contact members. The individual members of each pair are of substantially the same shape except that they are of reversed form as shown in Fig. 3. Each contact member such, for example, as 26, is preferably formed of a single piece of thin flat metal bent into a U-shaped formation with the two spaced and substantially parallel arm portions 71 and 72 joined by a connecting portion 73 to which the lead conductor is attached. The arm portions 71 and 72 are provided at one side with lips 74 and 75 to receive and guide the ends of the contact pins of the lamp between the arm portions, and may be provided at the opposite side with projecting portions 76 and 77, only one of which shows up in Fig. 12. While the projecting portions 76 and 77 have been shown as hook-shaped, it is to be understood that they may be straight or in any other desired shape.

When a pair of contact members, such as 26 and 27, are placed in the carrier 23, as shown in Figs. 3 and 4, the hook-shaped portions 76 and 77 on each pair of contact members are in opposed relation extending toward each other and above the inner face of their associated carrier 23 in such position as to hook over the opposed edges 68a and 69a of the openings 68 and 69 in the plate 29. This arrangement is shown in Fig. 4 wherein the hook shaped portions 76 and 77 of contact members 27 extend through the small opening 69.

It will be readily understood that this arrangement functions to hold the plate in its proper position on the carrier during assembly of the lamp holder and also to keep it in proper position with respect to its associated carrier in the lamp holder assembly as the carrier moves or adjusts itself with the housing.

The plates 28 and 29 serve to insulate the two sets of contact members from each other, hold the contact members in place and reduce friction between the two contact assemblies so that each may move freely within its recess independently of the other.

Fig. 15 shows how a pair of these double sided holders 81 and 82 may be used to support and conduct current to a pair of semi-circular lamps 83 and 84. The lamps, which are provided with a pair of contact pins at each end, are simply plugged into the opposite sides of the holders to form a complete circle. It will be apparent that other arrangements of lamps and holders may be made as desired.

10 In view of the foregoing, it will be apparent that my invention provides a lamp holder particularly suitable for use with semi-circular lamps for supporting such lamps in various arrangements or configurations. The holder is so constructed that it may be used in conjunction with another holder to support and provide good electrical connection for a single lamp or a pair of lamps, any one of which may have considerable manufacturing variation in their lengths 15 and relative positions of their contact pins. This is made possible in the case of any single lamp by use of floating contact assemblies mounted within the supporting housing for a limited amount of movement in such directions as to compensate for manufacturing variations in the single lamp; and in the case of a pair of lamps by having separate and independently movable contact assemblies in each housing. In addition, this double-sided holder is made up of 20 pairs of identical parts and the working parts or elements of the holder are held in their working positions by means of the two identical housing sections. The leads are so attached to the contact members of each assembly and mounted within the housing that they do not in any way interfere with the free movement of the contact assembly. In addition, the ends of the leads are securely clamped or gripped between the bottom edges of the housing sections as to provide 25 adequate strain relief for those portions of the leads and contact members within the housing.

30 While my invention has been described in detail using a lamp holder of the double-sided type as an example, it is to be understood that the principles of my invention also may be applied to a lamp holder of the single-sided construction with equal advantage.

35 It will also be apparent that even though a specific embodiment of my invention has been described, various changes may be made therein without departing from the fundamental principles of the invention.

40 I claim as my invention:

45 1. A lamp holder comprising, a hollow housing having a face portion with spaced openings therein, an insulating contact carrier mounted within the housing behind said spaced openings and also having spaced openings defined by integral bosses extending into the spaced openings of the housing, said carrier being movably mounted within the housing for movement in a plane parallel to the plane of said one face of the housing, contact members mounted on the carrier adjacent the spaced openings therein, and said bosses being considerably smaller in size than said housing openings so as to be accessible through said housing openings throughout a limited range of movement of said carrier relative to said housing.

50 2. A lamp holder for use with semi-circular electric discharge lamps having contact pins at the opposite ends comprising, a housing of insulating material having a cavity therein and a pair of spaced openings in a face portion thereof communicating with the cavity through which the 55 contact pins of the lamp may be inserted, said

60 65 70 75

openings having their centers on a line disposed at an angle to the longitudinal axis of the housing, a plate-like insulating carrier mounted within the housing in said cavity for limited movement therein for movement in a plane parallel to the plane of said one face of the housing, a pair of resilient contact members mounted on the carrier in registering relation with said face openings in definitely spaced relation to receive the lamp pins, and each of said contact members having a contact pin receiving opening considerably smaller in size than said housing openings so as to be accessible through said housing openings throughout the limited floating movement of said carrier relative to said housing thereby to provide a holder having a floating contact assembly which automatically adjusts itself when the lamp pins are inserted to compensate for permissible manufacturing variation of the lamp dimensions.

3. A lamp holder comprising, a hollow housing having a pair of spaced openings in each of a pair of opposite faces thereof, a contact member in the housing behind each of said openings, the openings in one of said faces being angularly displaced relative to the openings in the opposite face and the interior of said housing having terminal pin receiving recess means freely communicating with the openings in one face of the housing and overlapping terminal pin receiving recess means which freely communicate with the openings in the opposite face of the housing, whereby lamp terminal pins of two separate lamps may be inserted in its openings in the opposite faces of the housing, respectively, and be positioned in overlapping relation in the housing.

4. A lamp holder for use with semi-circular electric discharge lamps having contact pins at the opposite ends comprising, a hollow housing having oppositely disposed flat face portions, a pair of spaced elongated openings in at least one face portion through which the lamp pins may be inserted, said openings having their centers positioned on a line disposed in predetermined angular relation to the longitudinal axis of the housing, a contact carrier of insulating material slidably mounted within the housing back of said openings, said carrier having bosses on one side thereof extending into the spaced openings in said one face of the housing and having openings therein to receive the lamp pins, and electrical contact members mounted on the other side of the carrier to be engaged by the lamp pins.

5. A lamp holder for use with semi-circular electric discharge lamps having contact pins at the opposite ends comprising, a hollow housing having oppositely disposed flat face portions, a pair of elongated openings in each face portion with the centers of one pair of openings positioned on a line disposed in predetermined angular relations to the longitudinal axis of the housing and to a line extending through the centers of the other pair of openings, contact carriers of insulating material loosely mounted within the housing in back-to-back relation behind the openings in each face portion thereof, respectively, said contact carriers having openings registering with the elongated openings in the face portions and spaced to receive the lamp pins, and contact members mounted on the sides of the carriers which are adjacent each other at points adjacent the openings in the carriers to be engaged by the lamp pins when inserted through the elongated openings in the face portions of the housing.

6. A lamp holder for use with double-ended electric discharge lamps having spaced contact

pins extending from the ends thereof comprising, a hollow-body member having a pair of spaced openings in a face portion thereof, said openings having their centers positioned on a line extending at an angle of approximately 45 degrees to the longitudinal axis of the body member, an insulating contact carrier loosely mounted within the body member behind the openings for limited movement laterally as well as longitudinally of the body member, and contact members mounted on the carrier in fixed spaced relation to receive the contact pins of the lamp through the spaced openings in the face portion of the body member, and each of said contact members having a contact pin receiving opening considerably smaller in size than said housing openings so as to be accessible through said housing openings throughout the limited floating movement of said carrier relative to said housing.

20 7. A lamp holder for use with tubular discharge lamps of the semi-circular type having contact pins at the ends thereof comprising, a housing of insulating material formed of two complementary sections with oppositely disposed substantially parallel flat face portions with spaced openings therein, said housing sections being recessed on their inner faces to form a cavity between the openings in the opposed faces, a pair of flat contact carriers of insulating material disposed in said cavity, said carriers being slidably mounted in the cavity, a pair of contact elements mounted in fixed spaced relation on each carrier and communicating with the openings in the face portions of the housing to receive the contact pins of the lamps therethrough, said carriers and their associated contact members forming floating contact assemblies which are each freely movable within the housing to compensate for manufacturing inaccuracies in the dimensions of the lamps.

40 8. A lamp holder comprising, a hollow housing having oppositely disposed flat face portions with a pair of spaced openings in each face portion, a pair of contact carriers mounted in the housing between the flat face portions thereof and also having spaced openings registering with the openings in the faces of the housing, said carriers being separately mounted for movement in said housing so as to be movable with respect to the housing and to each other, and a pair of contact members mounted on each carrier adjacent the spaced openings therein.

9. A lamp holder comprising, a hollow housing having oppositely disposed flat face portions with a pair of spaced openings in each face portion, a pair of insulating contact carriers mounted within the housing in back to back relation between the flat face portions thereof for movement with respect to the housing and to each other and having spaced openings registering with the openings in the faces of the housing, said carriers being recessed on their opposed back faces for mounting contact members thereon adjacent the spaced openings therein, contact members mounted in said recesses, and a pair of insulating plates disposed between the opposed back faces of the carriers.

70 10. A lamp holder comprising, a hollow housing having oppositely disposed flat face portions with a pair of spaced openings in each face portion, a pair of contact carriers formed of insulating material mounted within the housing in back to back relation between the face portions thereof for movement both relative to the housing and to each other and having spaced openings de-

fined by bosses extending with the spaced openings in the opposite face portions of the housing, said carriers having recesses on their opposed back faces individual to each opening, contact members positioned in said recesses adjacent to each opening, said contact members having hook portions extending beyond the surfaces of the carriers, and a pair of plates of insulating material mounted between the carriers, said plates each having openings spaced to receive the hook portions of their respective pairs of contact members.

11. A lamp holder comprising, a hollow housing having oppositely disposed flat face portions with a pair of spaced openings in each face portion, a pair of contact carriers of insulating material slidably mounted within the housing in back to back relation between the face portions thereof for movement relative to the housing and independently of each other and having spaced openings registering with the spaced openings in the sides of the housing, said openings in one carrier and in the adjacent side of the housing being disposed in different angular relation with respect to the openings in the other carrier and its adjacent side wall of the housing, said carriers each having recesses in their opposed back faces individual to the spaced openings therein and additional recesses individual to and registering with the spaced openings in the recesses individual to the spaced openings of the other of said carriers, and a pair of plates of insulating material positioned between the carriers, each of said plates having openings registering with the recesses in their associated plates.

12. A lamp holder comprising, a hollow housing of two-piece construction formed of complementary sections recessed on their adjacent faces to provide a generally rectangular cavity with passages extending therefrom to the exterior of the housing, at least one of said sections having spaced openings therein into the cavity, a contact carrier of insulating material mounted in the cavity for sliding movement in a plurality of directions, a pair of contact members mounted on the carrier in registering relation with said spaced openings, insulated lead wires extending into the housing to the contact members on the carrier through said passages in the housing, said pas-

5 sages being provided with transverse projections formed to tightly engage the lead wires when the housing sections are pulled together, and fastening means for holding the housing sections together.

13. A lamp holder comprising, a hollow housing having oppositely disposed flat face portions with a pair of spaced openings in each face portion, a pair of contact carriers of insulating material slidably mounted within the housing in back-to-back relation between the face portions thereof for movement relative to the housing and independently of each other and having spaced openings registering with the spaced openings in the sides of the housing, said openings in one carrier and in the adjacent side of the housing being disposed in different angular relation with respect to the openings in the other carrier and its adjacent side wall of the housing, said carriers each having recesses in their opposed back faces individual to the spaced openings therein and additional recesses individual to and registering with the spaced openings in the recesses individual to the spaced openings of the other of said carriers, 20 and a pair of plates of insulating material positioned between the carriers, each of said plates having openings registering with the recesses in their associated plates.
